BURNETT KAVANAGH.

BY

Frank M. Ashley

ATTORNEY

UNITED STATES PATENT OFFICE

BURNETT KAVANAGH, OF NEW YORK, N. Y.

VENTILATOR

Application filed March 5, 1930. Serial No. 433,231.

My invention relates to ventilators used in window casings.

The object of my invention is to provide a ventilator which may be made as an independent article of manufacture and may be readily secured in position in the window casing, and which comprises means for holding a window shade, and which may also serve to hold curtains, and prevent them and the shade from being moved by the flow of air into the room. A further object of my invention is to provide a ventilator so formed as to protect the shade and curtains from becoming soiled by dust carried by the inflowing air currents.

A further object is to make the ventilator in two or more sections which are relatively adjustable so that they may be made to fit in window casings of various widths.

Referring to the drawings which form a part of this specification:

Fig. 1 is a cross-sectional view thru the upper part of a window casing, showing my improved ventilator in position, with a shade held therein, and shown in cross-section.

Fig. 2 is an elevational longitudinal view of the ventilator.

Figs. 3 and 4 are oppositely disposed end views thereof.

Fig. 5 is a perspective view of a ventilator in which the end plates do not extend entirely across the width of the ventilator, the shade brackets being formed as illustrated.

10—indicates the outer window casing and 35 11—the inner casing. 12—indicates the outer window which is lowered to permit air to flow above same and over the top of the ventilator 13—which extends entirely across the window casing and may be held at each 40 end by one or more screws which extend thru holes 14—formed in the end plates 15—or the holes 16—formed in the tabs 17—of the ventilator casing 13—when made in a single piece or 13— and 13'—when made in two 45 parts.

I prefer to make the ventilator of sheet metal, such as iron, which may be enamelled in any desired color, or brass which may be polished and lacquered.

50 The ventilator, together with the shade

brackets may be formed in one piece of sheet metal which is made long enough to extend entirely across the window casing with its ends abutting the same, and this is preferable when a complete building is to be 55 equipped with the ventilators, but when providing same for sale to the general trade I prefer to make them in two parts, as illustrated in Figure 2, one section being formed with overturned edges 18—and 19—to provide longitudinally extending grooves 20—and 21—respectively, to receive the edge portions 22—and 23—of the opposite section and arranged to telescope as illustrated in Figure 2, to permit adjustment for the 60 65 purpose stated.

In Figures 1, 2, 3 and 4 I have shown the ventilator constructed with end plates or walls 24—and 25—respectively, one plate having a hole 26—to hold one end of the 70 shade-roller and the other plate having a slot 27—to hold the other end.

In Figure 5 the shade brackets are provided by forming a tab 28—on each end of the ventilator to hold the shade in position 75 thereon. The tabs 17—may be bent to rest in alignment with the back sheet of the casing to permit the tabs to overlie the front panel of the window casing and be attached thereto by screws, or may extend parallel 80 with the wall of the end plates 24—and 25—as shown, to hold the ventilator in the window casing as shown in Figure 1.

The back wall 29—of the ventilator extends well below the position of the shade 85 roller 30—and provides a shield for the curtains 31—. 32—indicates the shade carried by the shade roller, and protected from the air currents flowing above the window sash 33—into the room in which the ventilator is 90 located.

The inner edge of the hood 34—of the 95 ventilator is provided with holes 35—to receive wire hooks 36—which support the curtain 31.

The end plates 24—and 25—are formed with inwardly extending offset portions 26'—and 27'—with the hole 26—and slot 27—formed therein, as illustrated, to support the 100 ends of the shade roller in the usual manner.

As illustrated, the hood portion of the ventilator is preferably formed with a curved surface, which prevents dust from collecting thereon better than when formed with a flat top, but it may be of any form desired which will serve the purpose above set forth.

The methods of making articles of sheet metal are so well known that further detailed description is unnecessary, further than to state that the ventilator should be made of thin stiff metal to reduce the weight, and by the use of the end plates 24— and 25— the hood is stiffened and strengthened as a whole.

Having thus described my invention, I claim as new:

1. A ventilator of the character described comprising a sheet of suitable material formed to provide an upwardly extending back wall and a hood portion adapted to 20 cover and partially inclose a shade with the forward edge of the hood terminating forwardly of the shade and extending beyond the length thereof whereby the shade may be removed from the ventilator when the 25 latter is in mounted position and adapted to be held at each end to the sides of a window casing.
2. A ventilator of the character described comprising a sheet of suitable material 30 formed to provide an upwardly extending back wall and a hood portion adapted to cover and partially inclose a shade with the forward edge of the hood terminating forwardly of the shade and extending beyond the 35 length thereof, and adapted to be held at each end to the sides of a window casing, and having a shade-bracket carried at each end thereof to support a shade under said hood with the shade removable while the ventilator is in mounted position.
3. A ventilator of the character described comprising a plurality of sheets of suitable material each having an upwardly extending back wall portion and a hood portion adapted 45 to cover a shade with the forward edge of the hood terminating forwardly and upwardly of the longitudinal axis of the shade, and means for connecting said portions in overlapping adjustable relation.
4. A ventilator of the character described comprising a plurality of sheets of suitable material each having an upwardly extending back wall portion and a forwardly curved hood portion adapted to cover a shade with 55 the forward edge of the hood terminating to provide a hood of substantially semi-circular formation and means for connecting said portions in overlapping adjustable relation, and having end portions each of which has 60 means to support one end of a shade roller, with the shade roller removable while the hood is in mounted position.

In testimony whereof I have affixed my signature.

65 BURNETT KAVANAGH.
